AUTOMATIC FEED CAULKING GUN

Robert G. Ames, Hillsborough, Calif., assignor of one-fourth to Stanley Ames, one-sixth to Katherine A. Williams, one-sixth to Lois W. Rosebrook, and one-sixth to George W. Williams III, Hillsborough, Calif.

Application August 21, 1956, Serial No. 605,250

9 Claims. (Cl. 72—130)

The present invention relates to improvements in an automatic feed caulking gun. It consists of the combinations, constructions and arrangement of parts, as herein-after described.

In my copending application on a "Self-Contained Dry Wall Taper," Serial No. 454,563, filed in the United States Patent Office on September 7, 1954, now Patent No. 2,815,142, there is disclosed a tool having a hollow handle, which is adapted for holding a supply of mastic. As shown therein, the tool is designed for extruding the mastic over a seam defined by wall boards, and simultaneously applying a strip of tape over the mastic.

Although certain structural features of the above-identified copending application are carried forward into the present disclosure, the caulking gun herein shown is designed for applying a ribbon of mastic to a stud, joist or other building member. Such a mastic, which has a rubber base, may be utilized for securing a wall board to the stud, joist or the like, without requiring the use of nails. However, the tool is not limited to the use of rubber base mastics. Moreover, the caulking gun may be employed for filling a groove in a building structure.

Briefly stated, the present automatic feed caulking gun includes a tubular handle having a bore adapted to contain a supply of mastic. The gun is provided with a mastic-delivering nozzle arranged at one end of the handle, and this mastic is forced through a conduit from the handle to the nozzle by means of a piston. The latter is advanced along the bore of the handle by a cable, which is wound upon a drum, as the tool is advanced along the stud, joist or other building member.

This drum is turned by a traction wheel and a drive mechanism. Experience has shown that operators are prone to force the traction wheel, when an insufficient amount of mastic is being delivered from the nozzle; and this may result in breaking the cable, as the piston reaches the forward end of its stroke.

Accordingly, and as one of the cardinal objects of this invention, it is proposed to automatically disengage the drive mechanism from the drum, as the piston completes its forward stroke, thus precluding the breaking of the cable.

Broadly speaking, the caulking gun is advanced along the building member, as the mastic is delivered thereto, and thus the handle is moved into various angular positions relative to the member to which the mastic is being applied. As another important object, therefore, I propose to provide a mastic-delivering nozzle that is designed to maintain contact with the building member, as the handle moves through various angular positions.

As a still further object of the invention, it is proposed to arrange a guide on the caulking gun, which will aid materially in assisting the operator in moving the gun along the stud, joist or other building member, when the mastic is being applied thereto.

Another object is to provide a valve, which is automatically opened as the mastic-delivering nozzle is being advanced, the valve being closed again upon removing the caulking gun from the stud, joist or other member of the building.

Other objects and advantages will appear as the speci-

2

fication proceeds, and the novel features of the invention will be set forth in the claims appended hereunto.

Drawings

5 For a better understanding of my invention, reference should be had to the accompanying drawings, forming part of this specification, in which:

Figure 1 is a fragmentary top plan view of the forward portion of my automatic feed caulking gun, parts being shown in section;

10 Figure 2 is a side elevational view of Figure 1, with a gear housing removed, and showing the gun prior to being pressed against a wall stud;

15 Figure 3 is an elevational view of the caulking gun, disclosing it after being urged against a wall stud and being advanced therealong;

20 Figures 4 and 5 are transverse sectional views taken along the vertical planes IV—IV and V—V, respectively, of Figure 2;

25 Figure 6 is a side view of the complete caulking gun, on a reduced scale, with part of the tubular handle being illustrated in section;

Figure 7 is a sectional view suggesting a wall board as being secured to studs, or joists, by ribbons of mastic;

25 Figure 8 is a fragmentary top plan view of my caulking gun, with an offset mastic-delivering nozzle arranged to fill a groove in a building structure, which groove is aligned with the traction wheel to serve as a guide for the latter; and

30 Figure 9 is a side elevational view of Figure 8, with the modified gun being advanced along the building structure.

35 While I have shown only the preferred forms of my invention, it should be understood that various changes, or modifications, may be made within the scope of the annexed claims without departing from the spirit thereof.

Detailed description

Referring now to Figures 1 to 6, inclusive, of the drawings, my automatic feed caulking gun is designated generally at A. It includes a tubular handle B adapted to contain a supply of mastic C. This handle preferably has a sufficient length as to permit an operator to utilize the gun, while standing on a floor and applying mastic to a ceiling joist.

45 The mastic utilized is well known in the art, and has a rubber base; it may be utilized for anchoring a plaster board to studs or ceiling joists, without requiring the use of nails. As previously stated, the gun is not limited to the use of rubber base mastics.

50 As disclosed in the drawings, a mastic-delivering nozzle D is arranged adjacent to one end of the handle B; and a mastic-feeding conduit E places the bore 10 of the handle in communication with the nozzle, whereby mastic C may be transferred from the bore to the nozzle. Figure 4 clearly shows the interior of the conduit E as communicating with the interior of the nozzle D. Thus the mastic may flow from the conduit to the nozzle, as suggested by the arrow 10a in Figure 1. In actual practice, the conduit E is made in sections E¹ and E², which are removably secured together by screws 9 (see Figure 2).

55 With particular reference to Figures 1, 2 and 6, it will be observed that a piston F is mounted in the bore 10 in back of the supply of mastic, the piston being movable toward the nozzle D to advance mastic C to the latter.

70 For the purpose of advancing the piston E, a drum 11 is rotatably mounted in the section E¹ of the conduit E so as to extend transversely across the latter. As shown in Figures 1 and 5, one end of the cable 12 is anchored to the drum by a screw 13, or other suitable fastening

means, which is disposed adjacent to one end of the drum. The opposite end of the cable is secured to a nut 14, the latter being threaded upon a rod 15. With particular reference to Figures 1 and 6, it will be noted that this rod is anchored to the piston F, and is provided with a guide disc 16 that is slidably disposed in the bore 10 of the handle B. This arrangement prevents the piston from tilting, but permits it to slide and rotate relative to the handle as the piston is pulled forwardly in the bore.

As illustrated in Figure 1, a disc 17 is clamped to the piston F by the nut 14 and the rod 15, and is fashioned with an opening 18 through which the rear end of the cable 12 passes. Thus the cable is guided to the piston in offset relation with respect to the piston axis, whereby the piston may turn as the cable is wound on the drum 11 from one end of the latter toward its other end, as disclosed in Figure 1 of the drawings. This will permit the cable portion between the drum and the piston to lie in a transversely moving plane that extends substantially at right angles to the drum axis at all times.

In order to force the mastic C through the conduit E and the nozzle D, a traction wheel G is provided. This wheel has its periphery fashioned with teeth 19. These teeth are engageable with a building member H against which a ribbon 20 of the mastic C may be extruded (see Figure 3). As previously mentioned, this member may be a stud, joist, or the like, to which a wall board 21 is to be attached by means of the mastic (see Figure 7). A pawl 19a engages with the teeth 19 so as to normally prevent reverse movement of the traction wheel.

It will be observed from Figure 4 that the traction wheel G has its hub 22 secured to a transversely-extending shaft 23 by means of a set-screw 24. This shaft is journaled in bearings 25 and 26 provided on the interiors of the nozzle D and the conduit section E², respectively. The traction wheel is disposed in parallel relation with respect to the nozzle D (see Figures 1 and 4), and is arranged at one end of the shaft 23. The opposite end of this shaft has a drive pinion 27 secured thereto.

As the traction wheel G is advanced along the member H in engagement therewith, as suggested by the arrow 28 in Figure 3, the wheel will be turned in the direction of the arrow 29, thus rotating the pinion 27. For the purpose of turning the drum 11, a drive mechanism J has been provided. Although a series of gears has been shown in Figure 2 as constituting this drive mechanism, it will be obvious that a chain and sprocket drive could be substituted therefor. The mechanism J includes a driven gear 30, which is disposed in axial relation with respect to the drum 11 (see Figures 1, 2 and 5).

It is important that the drum 11 be automatically disengaged from the drive mechanism J, when the piston F approaches the forward end of its stroke. This will preclude the breaking of the cable 12 upon further rotation of the traction wheel G. Experience has shown that an operator may force the traction wheel along the member H when the mastic C stops flowing from the nozzle D, even though the piston F has completed its stroke. This is due to the fact that the piston is enclosed by the tubular handle B and cannot be observed by the operator. For this reason, an automatic clutch K has been provided.

Reference is made to Figures 1, 2 and 5, wherein it will be seen that the drum 11 is rigidly connected to a hollow shaft 31 by a set-screw 32. This shaft has the web 33 of a channel-shaped bar 34 welded thereto, and this bar constitutes one element of the clutch K. A drive dog 35 is swingably attached by a pivot pin 36 to the channel bar 34, and carries a locking detent 37 that projects through an opening 38 formed in the web 33. Moreover, a spring 39 is anchored to this web and yieldingly urges the detent 37 into any one of a series of radial slots 40 fashioned in the gear 30 (see Figure 2).

When the locking detent is projected into one of the slots 40 by the spring 39, rotation of the gear 30 by the drive mechanism J will cause the drum 11 to turn, thereby pulling the piston F forwardly and thus extruding mastic C from the nozzle D. However, when the piston approaches the forward end of its stroke, it will engage with a clutch-operating rod 41 that is arranged in the path of the advancing piston (see Figure 1).

As the piston continues to advance, the rod 41 will swing a bell-crank lever 42. The latter is provided with a depending finger 43, which is arranged to move a disc 44 toward the drum 11. This disc is fixed to a spindle 45, which extends axially through the hollow shaft 31 so as to abut the drive dog 35. Accordingly, when the rod 41 is pushed forwardly by the piston F, the detent 37 will be disengaged from the driven gear 30, at which time the clutch K will be disengaged. A stop 46 is carried by the conduit section E¹ so as to limit the movement of the disc 44 away from this conduit.

The structural details of the mastic-delivering nozzle D is illustrated in Figures 1 to 4, inclusive. It is mounted for swinging movement about the shaft 23, which coincides with the axis of the traction wheel G. This nozzle has an outlet end provided with a surface 47 arranged to abut the member H to which the ribbon 20 of mastic is to be applied. As suggested by the dot-dash line 48 in Figure 2, the surface 47 defines a plane arranged tangentially to the periphery of the traction wheel G. Thus the surface 47 of the swingable nozzle will maintain contact with the member H, as the caulking gun A is advanced therealong, regardless of the angular relation of the handle B with respect to this member.

In Figure 3, a spring 49 has been illustrated as having one of its ends attached by a pin 50 to the mastic-delivering nozzle D, while its other end is secured to an eyelet 51 fixed to the conduit E. This construction will yieldingly urge the nozzle to a predetermined normal position, as shown in Figure 2, when the caulking gun is removed from the member H. At this time, the nozzle will abut an adjustable screw 52, which is carried by a bracket 53 fixed to the conduit section E².

The nozzle D has an outlet opening 54 fashioned therein, through which the ribbon 20 of mastic is discharged against the member H. A valve 55 is disposed to control the outflow of the mastic from the nozzle, and this valve normally closes this opening, as disclosed in Figure 2. However, a valve-actuating device L is operable to automatically open the valve 55, when the nozzle is swung in a counterclockwise direction in Figure 2, and to close the valve upon the swinging of the nozzle in the opposite direction.

In its structural features, the valve-actuating device L includes a cam 56, which is fixed to the mastic-feeding conduit E, and a lever 57 operatively connected to the valve, this lever having an end 58 bearing against the cam. When the valve 55 is closed, the end 58 of the lever projects into a recess 59 fashioned in the cam. As the nozzle D swings in a counterclockwise direction in Figure 2, the end 58 of the lever 57 rides out of the recess 59, and the cam will move the valve 55 so as to uncover the outlet opening 54 (see Figure 3). Upon withdrawing the caulking gun A from the member H, the spring 49 will swing the nozzle D back into the position illustrated in Figure 2; and a hook 60 on the cam will engage with the lever end 58, causing the latter to re-enter the recess 59, thus closing the valve.

As an important structural detail, a guide wheel M is secured to the traction wheel G by screws 61 (see Figure 4). Spacers 62 are interposed between these wheels so as to maintain them in separated relation with one another. A gasket washer 62a is interposed between the nozzle D and the wheel G. It will be apparent that the guide wheel is larger in diameter than the traction wheel so that a peripheral section of the wheel M will engage with a lateral edge 63 of the member H and

move therealong, whereby the mastic will be extruded from the nozzle at a predetermined distance from the edge 63, as will be obvious by reference to Figure 1.

For the purpose of protecting the driven mechanism J and the clutch K, a housing 64 may be removably secured to the conduit E by screws 65, or other suitable fastening means.

Of course the supply of mastic C must be replaced in the tubular handle B from time to time. Accordingly, a filling tube 66 has been provided which extends through the section E¹ of the conduit E so as to communicate with the forward end of the bore 10. Any suitable pump (not shown) may be utilized for forcing the mastic through the tube 66. As the handle is thus filled, the mastic will push the piston F rearwardly. As indicated in Figure 1, a spring-pressed valve 67 automatically closes the tube 66 when the pump is withdrawn therefrom. My copending application, Serial No. 454,563 discloses a pump suitable for this purpose.

Turning now to the modification illustrated in Figures 8 and 9, the same mastic-feed caulking gun A is employed, with the exception that the guide wheel M has been omitted, and a modified, nozzle D¹ has been substituted. Like reference numerals have been applied to corresponding parts of the two embodiments of the gun.

This modified nozzle has an offset portion 68 that is arranged in the plane of the traction wheel G, and it is designed for delivering mastic C through its outlet opening 54a to a groove 69 formed in a building structure H¹. As shown in Figure 9, the traction wheel G may be pressed into the groove 69 so as to guide the gun along the structure H¹, while a ribbon 20a of the mastic is delivered into the groove. Inasmuch as the groove 69 serves as a guide for the traction wheel, no guide wheel is required in this form of the caulking gun.

Summary of operation

The operation of the first embodiment of my automatic feed caulking gun A, as disclosed in Figures 1 to 6, inclusive, is summarized briefly as follows:

Assuming that the tubular handle B contains a supply of the mastic C, and that the operator desires to secure wall boards 21 to the studs H (or other building structure), by ribbons 20 of the mastic (see Figure 7), the operator first moves the mastic-delivering nozzle D against the stud, with the guide wheel M aligned with the lateral edge 63 of the stud (see Figures 1 and 2). Then the gun is pushed toward the stud until the surface 47 of the nozzle contacts with the stud and the traction wheel G contacts the stud. At this time, a peripheral section of the guide wheel M will overlap the stud and the valve 55 will be opened automatically (see Figure 3).

As the gun is advanced along the stud, as suggested by the arrow 28, the traction wheel will be rotated in the direction of the arrow 29. This will cause the drive mechanism J to turn the drum 11; and, through the medium of the cable 12, the piston F will be drawn forwardly in the bore 10 of the handle. This will result in extruding a ribbon 20 of the mastic against the stud at a predetermined distance from the lateral edge 63 of the stud. The nozzle will swing against the action of the spring 49, as the gun is advanced, and thus the surface 47 will maintain contact with the stud.

As the piston reaches the forward end of its stroke, it will push the clutch-operating rod 41 forwardly, resulting in disengaging the clutch K. This will permit the driven gear 30 to turn freely on the hollow shaft 31; and thus the cable 12 will not be broken, in the event that the operator should attempt to continue pushing the gun along the stud. At any time that the operator removes the gun from the stud, the nozzle D will be returned to its normal position (see Figure 2) by the spring 49 and the valve 55 will close automatically.

When filling the groove 69 of the building structure

H¹ with mastic, the modified nozzle D¹ is utilized (see Figures 8 and 9). Here, the offset mastic-delivering portion 68 of the nozzle will insert ribbon 20a of the mastic into the groove 69, while the traction wheel G rides along the bottom of this groove, with the walls of the groove serving to guide the forward movement of the caulking gun along the building structure. Otherwise, the operation of this form of the invention is the same as that previously described in connection with the first embodiment.

I claim:

1. In an automatic feed caulking gun: a tubular handle having a bore adapted to contain a supply of mastic; a mastic-delivering nozzle arranged adjacent to one end of the handle; a mastic-feeding conduit placing the bore of the handle in communication with the nozzle, whereby mastic may be transferred from the bore to the nozzle; a piston mounted in the bore in back of the supply of mastic, and being movable toward the nozzle to advance mastic to the latter; a rotatable drum carried by the handle and having one end of a cable anchored thereto, with the other end of the cable being fastened to the piston; a traction wheel mounted adjacent to the nozzle and rotatable on an axis transverse thereto so as to be engageable with a member against which mastic is to be extruded when the gun is used; the wheel being rotatable when the operator moves the handle and advances the wheel along said member in engagement therewith; and a drive mechanism connecting the traction wheel with the drum for turning the latter when the wheel is rotated for winding the cable and moving the piston for forcing mastic out the nozzle; said drive mechanism including means operable for automatically disengaging the traction wheel when the piston reaches a predetermined point at the forward end of its stroke, thereby precluding the breaking of the cable upon further rotation of the traction wheel; said drum disengaging means including a clutch, and a clutch-operating rod arranged in the path of the advancing piston and adapted to be actuated by the piston when the latter reaches a predetermined point in its stroke for disconnecting the drum from the drive mechanism.
2. In an automatic feed caulking gun: a tubular handle having a bore adapted to contain a supply of mastic; a mastic-delivering nozzle arranged adjacent to one end of the handle; a mastic-feeding conduit placing the bore of the handle in communication with the nozzle, whereby mastic may be transferred from the bore to the nozzle; a piston mounted in the bore in back of the supply of mastic, and being movable toward the nozzle to advance mastic to the latter; a rotatable drum carried by the handle and having one end of a cable anchored thereto, with the other end of the cable being fastened to the piston; a traction wheel mounted adjacent to the nozzle and rotatable on an axis transverse thereto so as to be engageable with a member against which mastic is to be extruded when the gun is used; the wheel being rotatable when the operator moves the handle and advances the wheel along said member in engagement therewith; and a drive mechanism connecting the traction wheel with the drum for turning the latter when the wheel is rotated for winding the cable and moving the piston for forcing mastic out the nozzle; said drive mechanism including means operable for automatically disengaging the drum from the traction wheel when the piston reaches a predetermined point at the forward end of its stroke, thereby precluding the breaking of the cable upon further rotation of the traction wheel; the drum extending transversely across the forward end of the tubular handle and the piston being rotatable about its axis; the cable being guided to the piston in offset relation with respect to the piston axis, whereby the piston will be rotated as the cable is wound on the drum from one end of the drum toward its opposite end so as to permit the cable portion between the

drum and the piston to lie in a transversely moving plane that extends substantially at right angles to the drum axis at all times.

3. In an automatic feed caulking gun: a tubular handle having a bore adapted to contain a supply of mastic; a mastic-delivering nozzle arranged adjacent to one end of the handle; a mastic-feeding conduit placing the bore of the handle in communication with the nozzle, whereby mastic may be transferred from the bore to the nozzle; a piston mounted in the bore in back of the supply of mastic, and being movable toward the nozzle to advance mastic to the latter; a rotatable drum carried by the handle and having one end of a cable anchored thereto, with the other end of the cable being fastened to the piston; a traction wheel mounted adjacent to the nozzle and rotatable on an axis transverse thereto so as to be engageable with a member against which mastic is to be extruded when the gun is used; the wheel being rotatable when the operator moves the handle and advances the wheel along said member in engagement therewith; a drive mechanism connecting the traction wheel with the drum for turning the latter when the wheel is rotated for winding the cable and moving the piston for forcing mastic out the nozzle; said drive mechanism including means operable for automatically disengaging the drum from the traction wheel when the piston reaches a predetermined point at the forward end of its stroke, thereby precluding the breaking of the cable upon further rotation of the traction wheel; and a guide spaced laterally from the gun and being carried thereby; the guide being engageable with an edge of said member and movable therealong as the gun is moved, whereby the mastic will be extruded from the nozzle onto said member at a predetermined distance from said edge.

4. In an automatic feed caulking gun: a tubular handle having a bore adapted to contain a supply of mastic; a mastic-delivering nozzle arranged adjacent to one end of the handle; a mastic-feeding conduit placing the bore of the handle in communication with the nozzle, whereby mastic may be transferred from the bore to the nozzle; a piston mounted in the bore in back of the supply of mastic, and being movable toward the nozzle to advance mastic to the latter; a rotatable drum carried by the handle and having one end of a cable anchored thereto, with the other end of the cable being fastened to the piston; a traction wheel mounted adjacent to the nozzle and rotatable on an axis transverse thereto so as to be engageable with a member against which mastic is to be extruded when the gun is used; the wheel being rotatable when the operator moves the handle and advances the wheel along said member in engagement therewith; and a drive mechanism connecting the traction wheel with the drum for turning the latter when the wheel is rotated for winding the cable and moving the piston for forcing mastic out the nozzle; said drive mechanism including means operable for automatically disengaging the drum from the traction wheel when the piston reaches a predetermined point at the forward end of its stroke, thereby precluding the breaking of the cable upon further rotation of the traction wheel; the nozzle having an offset mastic-delivering portion arranged so that the nozzle outlet will deliver a layer of mastic whose center line is arranged in registration with the plane of the traction wheel.

5. In an automatic feed caulking gun: a tubular handle having a bore adapted to contain a supply of mastic; a mastic-delivering nozzle swingable about an axis transverse to the handle and arranged adjacent to one end of the handle; a mastic-feeding conduit placing the bore of the handle in communication with the nozzle; whereby mastic may be transferred from the bore to the nozzle; a piston mounted in the bore in back of the supply of mastic, and being movable toward the nozzle to advance mastic to the latter; means operable to advance the piston

and including a traction wheel whose axis coincides with the nozzle axis; and yielding means urging the nozzle to a predetermined inoperative position, the outer end of the nozzle projecting beyond the traction wheel periphery; the nozzle having an outlet end provided with a surface arranged to slidably abut the surface of a member against which the traction wheel bears and on which the mastic is to be extruded when the gun is used; the nozzle being swingable by the yielding means as the handle is moved along said member, so as to cause the nozzle to keep in contact with said surface on the member at all times and permit the handle to assume different angular positions with respect to said surface during the entire caulking operation.

6. The combination as set forth in claim 5; and in which a valve is mounted in the nozzle to control the outflow of mastic therefrom; and a valve-actuating device is connected to the handle and disposed adjacent to the nozzle and operatively connected to the valve for automatically opening it when the nozzle is brought into contact with the surface on the member and is swung into operative position; the valve-actuating device automatically closing the valve when the nozzle is removed from the member and said yielding means returns the nozzle to inoperative position.

7. In an automatic feed caulking gun: a tubular handle having a bore adapted to contain a supply of mastic; a mastic-delivering nozzle carried by the handle and communicating with the handle interior at one end thereof so as to receive mastic therefrom; said nozzle being swingable about an axis that extends transverse to the handle and having an outlet designed to lay a mastic ribbon on a surface paralleling the axis when the nozzle contacts the surface and is moved thereover; a piston mounted in the handle bore for forcing mastic from the bore and out through the nozzle; a traction wheel rotatable about the nozzle axis and supported by the gun; the radius of said wheel being less than the distance the nozzle outlet is removed from the axis; whereby the nozzle is adapted to contact with the same surface contacted by the traction wheel; piston-moving means operatively connecting the wheel with the piston so that a movement of the gun handle for causing the wheel to travel over the surface, will rotate the wheel and advance the piston for causing it to feed mastic through the nozzle and onto the same surface for depositing a mastic ribbon thereon; and spring means for yieldingly swinging the nozzle about its axis for causing it to contact with the surface regardless of the angular position of the handle with respect to the surface; said spring means swinging the nozzle into inoperative position when the nozzle is removed from the surface.

8. The combination as set forth in claim 7; and in which the portion of the nozzle projecting beyond the wheel periphery has a wall that is always tangent to the periphery and will ride on the surface contacted by the wheel; the outlet for the nozzle being related to the said nozzle wall for laying a mastic ribbon of the desired thickness and shape on the surface as the traction wheel moves thereover.

9. The combination as set forth in claim 7; and in which the nozzle has an offset portion with an outlet whose center lies in a plane coinciding with the plane of the traction wheel; said spring means being adapted to swing the nozzle for keeping the outlet of the offset portion in contact with a surface paralleling the surface contacted by the traction wheel.
